WILLIAM H. WOOD, OF SOUTH EUCLID, OHIO

HEADLIGHT

Application filed December 1, 1926. Serial No. 151,955.

This invention relates to vehicle headlights and has for its object the provision of a new and improved reflector, usable either alone or in conjunction with a lens of suitable type for 5 producing a light beam part of which shall be projected a long distance ahead of the vehicle in the form of a concentrated ray and other parts of which shall be cast downwardly and laterally at points nearer to the vehicle, 10 and this throughout a considerable range of vertical displacement of the light source. This last feature becomes necessary whenever a "two filament" lamp bulb is employed, having two independently usable sources 15 therein, spaced a short distance apart vertically, the purpose being to enable an elevation or depression of the reflected beam according to traffic conditions, while maintaining the light pattern substantially uniform. 20 Another object of the invention is to produce a reflector having the above-described characteristics which shall in addition exhibit a substantial degree of tolerance as regards axial displacement of the filament relatively to 25 the focal region, namely a degree of tolerance which is as great as the accidental variations between lamp bulbs of the same size, make, and type. This application is a continuation of my former application filed July 30 21, 1926, Serial No. 123,944, so far as the subject-matter is common thereto.

As set forth in my application filed February 26, 1926, and June 7, 1926, Serial Nos. 90,781 and 114,167 respectively, I make at 35 least the lateral margins of the reflector substantially paraboloid with its axis approximately horizontal, since the light pattern produced by this portion of the reflector is least distorted by such a vertical movement of the 40 light source as is produced by a change from one filament to the other. The rays falling on other parts of the reflector are cast downwardly and laterally by modifying the remaining portions of the reflector as herein- 45 after described.

In the drawings accompanying and forming a part of this application I have shown a preferred physical embodiment of my inventive idea. Figs. 1 and 2 are respectively a 50 side elevation and a front elevation of a re-

flector embodying my improvements; Fig. 1 being shown partly in section corresponding to the line 1—1 of Fig. 2; and Figs. 3 and 4 illustrate alternative modes of deriving the curve employed for the central vertical zone 55 illustrated in Fig. 2.

My improved reflector is characterized essentially by the relation between its horizontal section X—X and its vertical section Y—Y. The former section comprises a parabola with its axis $a-b$ substantially horizontal; the latter section comprises a parabolic curve having a greater downward inclination at every point than that of the paraboloid at an equivalent point. The portions A 60 and B of the reflector surface located adjacent to the horizontal section are preferably segments of a surface of revolution produced by revolving the horizontal parabola about its own axis $a-b$, and the focal point of this portion of the reflector is indicated at f^A in Fig. 1. If this surface of revolution were continuous it would produce the complete paraboloid indicated at A' B' by dotted lines in Figs. 1 and 2. In practice I use for reflecting purposes only that portion of such paraboloid as lies at and near the horizontal central plane at each side of the reflector, but show the remainder of such surface of revolution by dotted lines solely to facilitate this 70 description. 75

The vertical axial section corresponding to Y—Y in Fig. 2 conforms to a second parabola having its vertex located in front of the vertex of said first paraboloid. This 80 last curve can be either a simple parabola generated as shown in Fig. 3 or the curve illustrated in Fig. 4. The curve G illustrated in Fig. 3 is a simple parabola wherein every point is equidistant from the focal point f and from the line D—D perpendicular to the axis $a-a$ and known as the directrix. The curve H in Fig. 4 likewise has a focal point f' but the same is located above the axis $a'-a'$ and the curve itself is produced as follows. A directrix D'—D' is drawn perpendicular to the axis $a'-a'$. A line $m-m$ is drawn through the focal point f' and intersecting the axis $a'-a'$ at the point m' . Thereupon a vertical line M—M 90 95 100

is drawn parallel to $D'-D'$ as far on the opposite side thereof as m' is displaced laterally from the focal point. A point m^o is now found on this line equidistant from the line $M-M$ and the point m' and this is a point on the curve. Likewise a line $n-n$ is drawn through the focal point f' and intersects the line $a'-a'$ at n' . A vertical line $N-N$ is drawn parallel to $D'-D'$ and spaced the same distance inside of the latter as n' is displaced inwardly of the focal point and a point n^o is found on that line equidistant from $N-N$ and from n' . Likewise a line $p-p$ is drawn through the focal point intersecting the axis $a'-a'$ at p' and a vertical line $P-P$ is drawn parallel to $D'-D'$ and as far behind that line as p' is located in front of the focal point thus enabling the location of a point p^o equidistant from $P-P$ and from p' . The curve thus produced can be considered as essentially a parabola having its focal point displaced to one side of the axis $a'-a'$ and its axis $a''-a''$ inclined downwardly and forwardly compared with the first named axis. It will be noted that a line $S-S$ passing through the focal point f' is related directly to the directrix $D'-D'$, the points s^o-s^o being equidistant from such directrix and from the axis $a'-a'$. Either the parabola G shown in Fig. 3 or the modified parabolic curve H shown in Fig. 4 can be employed as a template for the central vertical zone $C-C$.

35 The essential thing is that the curve defined by the vertical section $Y-Y$ shall lean forwardly and downwardly at every point as compared with the paraboloid surface $A'-B'$ defined by the side wings; and it is desirable for practical reasons, though substantially immaterial optically, that the vertex of the curve which defines the vertical section be located in front of that of the horizontal section since in this way the front of the reflector becomes more nearly circular. Ordinarily the focal length of the curve defined by the vertical section $Y-Y$ is less than that of the parabola defined by the horizontal section $X-X$ so as in conjunction with the described relation of the vertices to bring said focal points substantially into the same vertical line but the relation of the focal points is much less important than that of the surfaces as defined in this paragraph and is not so good a criterion of my invention as the comparative inclination of the curves both because of possible variations and because of the difficulty of locating the focal point in an existing reflector.

40 It must not be supposed that the axis $c'-c'$ constitutes the axis of revolution about which the portion $C-C$ of the reflector is produced. The axis $c'-c'$ is merely the axis of the curve defined by the central vertical section; in other words of the vertical tem-

plate. Each half of the portion $C-C$ is produced by swinging the corresponding half of this template about an axis oblique to $c'-c'$ but much further away; for example, the upper half of this zone may be considered as swung about an axis $g-h$ and the lower half about an axis $k-l$.

5 In order to avoid difficulty occasioned by any angular meeting of the different surfaces and also to secure a convenient anchorage for the lamp socket I form a flat spot I at the heel of the reflector perpendicular to the axis $a-b$. It should also be noted that the transverse curvature of the portion $C-C$ is less than the curvature of the paraboloid $A'-B'$ adjacent to its vertex. It is for this reason the vertex of the portion $C-C$ should be located forward of the vertex of the paraboloid $A-B$ and this is an important feature of my invention, as well as being easily proven. In referring to these vertices I do not imply that either or both of the surfaces must be actually extended to or through the axis but refer more particularly to the imaginary extension of the surfaces as illustrated in Fig. 1 in dotted lines.

10 The portion C falls inside of and below the paraboloid $A'-B'$ at the top of the reflector. At the bottom center of the reflector the two surfaces may merge exactly as here shown, or either may fall somewhat within or without the other. This relation is not important optically, so long as the two lower outer margins of this portion fall below the paraboloid $A'-B'$ as indicated at $q-q$ in Fig. 2. Likewise the two upper margins of the portion C must always remain below the paraboloid $A'-C'$ as indicated at $r-r$ in Fig. 2. This same relation must prevail throughout the four remaining quadrants of the reflector, namely that the portions $E-E$ above the center must lie wholly below and inside, while the portion $E'-E'$ below the center must lie wholly below and outside of the paraboloid surface $A'-B'$ defined by the side wings. These can be regarded as transition surfaces gradually merging the edges of A and B with those of C . Obviously such a reflector is best produced by first making a metal punch according to the description heretofore given and when the same have been followed to this point it will be found that the remaining sections are comparatively small in area and very nearly matched in form so that it is an easy matter to fashion these quadrants into connecting surfaces. It is also permissible to flat some or all of the reflector into vertical striations, if desired. In case this is done, care must be taken not to obliterate the essential curvatures and relations heretofore described, namely that the vertical section conform to a parabola of one of the types mentioned, every point of which shall lean forwardly and downwardly as compared with the paraboloid which

constitutes the median horizontal zone and having its vertex located in front of the vertex of such paraboloid. It should be understood that the words "upper" and "lower," "above" and "below" and "downwardly" employed in this specification relate to positions compared with the earth's surface when the headlight is in its intended operative position on a vehicle.

Having thus described my invention what I claim is:

1. A headlight reflector whose horizontal axial section is parabolic at points adjacent to and extending inwardly from its lateral margins, and whose vertical axial section is parabolic at points adjacent to and extending inwardly from its upper and lower margins, the focal length of the vertical section being less than that of the horizontal section, and the vertex of the parabola which defines the vertical section being located in front of the vertex of the parabola which defines the horizontal section.

2. A headlight reflector whose horizontal axial section is parabolic at points adjacent to and extending inwardly from its lateral margins, and whose vertical axial section is parabolic at points adjacent to and extending inwardly from its upper and lower margins, the vertex of the vertical section being located in front of the vertex of the horizontal section and the axis of the vertical section being below the axis of the horizontal section, in front of the focal point thereof.

3. A headlight reflector having portions immediately adjacent its horizontal axis defined by segments of a paraboloid, and having a central vertical zone whose longitudinal section is defined by a parabolic curve having a focal point and an inclined axis, the focal distance of such curve being less than that of the first named paraboloid and the focal point of such curve being located in substantially the same vertical line with the focal point of said first paraboloid, the transverse section of said central zone being of less curvature than said paraboloid.

4. A headlight reflector whose horizontal section is in large part a parabola and whose vertical section both above and below the axis is in large part a parabolic curve of shorter focal distance than the first named parabola, the focal point of said last named curve lying substantially on the same vertical line with the focal point of said parabola.

5. A headlight reflector whose horizontal section is a parabola and whose vertical section is a parabolic curve of shorter focal distance than the first named parabola, the focal point of said last named curve lying substantially on the same vertical line with the focal point of said parabola and the axis of said last curve being downwardly inclined relative to the axis of said parabola.

6. A headlight reflector whose horizontal and vertical axial sections are both in large part substantially parabolic curves, the focal length of the vertical section being less than that of the horizontal section, the vertical central zone having a transverse curvature less than that of the horizontal zone and the axis of the vertical section being inclined forwardly and downwardly as compared with that of the horizontal section, and the vertex of the vertical section lying in front of that of the horizontal section.

7. A headlight reflector whose horizontal and vertical axial sections are both in large part substantially parabolic curves, the focal length of the vertical section being less than that of the horizontal section, the vertical central zone having a transverse curvature less than that of the horizontal zone, the vertex of the vertical section being located in front of the vertex of the horizontal section, and the heel of the reflector having a plane portion perpendicular to the reflector axis, which portion merges with both the horizontal and vertical zones.

8. A headlight reflector whose horizontal and vertical axial sections are in large part substantially parabolic curves of unequal size, the focal length of the vertical section being the smaller, the vertical central zone having a transverse curvature less than that of the horizontal zone, and the lateral margins of said central vertical zone being located outside of the paraboloid defined by said horizontal zone throughout all the region which lies below said horizontal zone, and inside of such paraboloid throughout all the region which lies above said horizontal zone.

9. A headlight reflector whose horizontal and vertical axial sections are in large part substantially parabolic curves of unequal size, the focal length of the vertical section being the smaller, the vertex of said vertical section being located in front of the vertex of said horizontal section, and said vertical section having a greater forward inclination at every point than is exhibited at equivalent points by the paraboloid defined by said horizontal zone.

10. A headlight reflector having portions at and for a substantial distance on each side of its horizontal axial plane defined by segments of a paraboloid surface, and having the portions at and near its vertical axial plane leaned forwardly and downwardly as compared with the first mentioned paraboloid surface at equivalent points, the vertex of all portions at and near the axial plane being located in front of the vertex of said paraboloid.

11. A headlight reflector having portions at and near its horizontal axial plane defined by a paraboloid surface whose axis is substantially horizontal and having the portions at and near its vertical axial plane conform-

ing in large part to a parabola which is everywhere leaned forwardly and downwardly as compared with said paraboloid at equivalent points, the transverse curvature of said last named portions being less than that of the first named portions, and the lateral margins of said last named portions lying everywhere below the paraboloid surface defined by said first named portions.

- 10 12. A headlight reflector having portions at and near its horizontal axial plane defined by a paraboloid surface whose axis is substantially horizontal, and having portions at and near the vertical axial section defined longitudinally by a curve which leans downwardly and forwardly as compared with said paraboloid and defined laterally by a line of smaller curvature than said paraboloid, the margins of said last named portions being 15 joined to the adjacent margins of said first named portions by segments which lie wholly below said paraboloid surface.

13. A headlight reflector having portions at each side extending both above and below the horizontal plane defined by a paraboloid surface whose axis is substantially horizontal, and having portions at and near its vertical axial plane which exhibit at every point a downward leaning as compared with the 20 extended surface of said first paraboloid at equivalent points, the margins of said last named portions being joined to the adjacent margins of said first named portions by segments which lie wholly below said paraboloid 25 surface, the portions of said reflector lying at each side of the central vertical zone themselves having vertical zones of reduced horizontal curvature superposed thereon.

In testimony whereof I hereunto affix my
40 signature.
